DESIGN FOR A COMBINED AIR HORN AND ACTUATOR

Harold F. Hadley, Defiance, Ohio

Application May 24, 1944, Serial No. 113,739

Term of patent 7 years

(Cl. D72—1)

To all whom it may concern:

Be it known that I, Harold F. Hadley, a citizen of the United States, residing at Defiance, county of Defiance, and State of Ohio, have invented a new, original, and ornamental Design for Combined Air Horn and Actuator, of which the following is a specification, reference being had to the accompanying drawing, forming part thereof.

In the drawing,

Figure 1 is an elevational view of combined air horn and actuator showing my new design;

Figure 2 is an elevational view of the combined air horn and actuator illustrating the air horn in a horizontal position;

Figure 3 is a top plan view of the combined air horn and actuator in the relative position as shown in Figure 2.

I claim:

The ornamental design for a combined air horn and actuator, substantially as shown.

HAROLD F. HADLEY.
